United States Patent Office

Des. 204,336
Patented Apr. 5, 1966

204,336

COPY HOLDER

James D. O'Donnell, 1955 79th St.,
Jackson Heights, N.Y.

Continuation of design application Ser. No. 72,082, Oct. 8,
1962. This application Sept. 15, 1964, Ser. No. 82,041

Term of patent 3½ years

(Cl. D74—1)

FIG. 1

FIG. 2

Des 204,336

PAGE 2

FIG. 3

FIG. 6

FIG. 1 is a perspective view of the copy holder embodying my design;

FIG. 2 is a top plan view;

FIG. 3 is a front elevational view;

FIG. 4 is a right-side elevational view;

FIG. 5 is a left-side elevational view; and

FIG. 6 is a rear elevational view thereof.

This application is a continuation of my co-pending application Serial No. 72,082 filed October 8, 1962, and now abandoned.

I claim:

The ornamental design for a copy holder, substantially as shown and described.
